FROZEN CONFECTION

Arthur S. Ensler, Scarsdale, and Aaron Friedman, New York, N.Y., assignors to Joe Lowe Corporation, New York, N.Y., a corporation of Delaware

Application October 23, 1956, Serial No. 43,473

Term of patent 14 years

(Cl. D82—2)

We claim:

The ornamental design for a frozen confection, as shown and described.
